APPARATUS FOR BUFFING BUMPER BARS

Thomas E. Robinson, Grosse Pointe, and Frank H. Hartlep, Detroit, Mich., assignors to Houdeille-Hershey Corporation, Detroit, Mich., a corporation of Michigan

Application April 28, 1947, Serial No. 744,344

1 Claim. (Cl. 51—217)

1

This invention relates to a machine for effecting the polishing or buffing of irregularly contoured surfaces. This machine has particular application to the polishing or buffing of arcuate end portions of bumper bars for modern automotive vehicles.

The current trends in automotive design have resulted in a one-piece bumper construction having arcuate end portions of considerable extent and departure from the central portion of the bumper. When such bumpers are assembled on a car, the central portion extends across the front of the car substantially parallel thereto, while the arcuate end portions extend generally around each side of the car and project a substantial distance rearwardly.

The manufacture of bumper bars of such configuration has heretofore been more expensive and time consuming through the lack of suitable machines for effectively polishing the curved end portions of the bumper bars. Such curved portions generally do not constitute circular segments, but are of non-circular arcuate configuration and hence cannot be conveniently polished on a machine of the conventional rotary table type. The problem is further complicated by the fact that most of such bumper bars have non-concentric cross sections, i. e., non-concentric about a medial plane passing through the length axis of the bar.

Accordingly, it is an object of this invention to provide an improved machine for effecting the polishing or buffing of irregularly contoured articles, and particularly, for polishing the arcuate end portions of modern bumper bars for automotive vehicles.

A particular object of this invention is to provide a polishing machine for rapidly and economically effecting the polishing of the arcuate end portions of bumper bars in which the only manual attention required is the loading of the bumper bars onto a conveyor portion of the machine at a loading station, the reversal of the bumper bars end for end at an intermediate station, and the unloading of the bumper bars from the bumper conveyor at the end of the polishing operation.

A further object of this invention is to provide a machine for polishing the curved end portions of bumper bars wherein clamps are provided on an endless conveyor for detachably securing a bumper bar thereon in such position that one of the arcuate end portions is disposed in general alignment with the direction of movement of the conveyor, whereupon the polishing of such one

2

arcuate end portion may be accomplished by rotating polishing wheels disposed along the path of movement of the conveyor.

Still another object of this invention is to provide an improved mounting for positioning bumper bars on the conveyor of a polishing machine which will automatically compensate for changes in spatial position of the arcuate end portions of such bumper bar when reversed end for end on the conveyor, which may result due to the fact that the bumper bars are of non-concentric cross sectional configuration.

The specific nature of the invention as well as other objects and advantages thereof will become apparent to this skilled in the art from the following detailed description of the annexed sheets of drawings which, by way of preferred example only, illustrate one specific embodiment of the invention.

20 On the drawings:

Figure 1 is a schematic view illustrating the path of a conveyor and operating stations employed in a machine embodying this invention for transporting the bumper bars past a plurality of rotating polishing wheels;

Figure 2 is an elevational view of a portion of the conveyor of a machine embodying this invention showing the bumper bars positioned thereon;

30 Figure 3 is a transverse sectional view taken on the plane III—III of Figure 2;

Figure 4 is an enlarged scale, front elevational view of one of the clamping elements employed for mounting the bumper bars on the conveyor; and

35 Figure 5 is a side elevational view of Figure 4, and shows in addition the position of a bumper bar when secured by the clamps.

As shown on the drawings:

40 As best shown in Figures 2 and 3, a machine embodying this invention comprises a generally rectangular, block-like frame structure 10 which may be conveniently fabricated by welding or riveting together of structural beam members. Such frame construction includes a plurality of spaced upright members 10a which are rigidly secured to and interconnected by generally horizontal base members 10b. Adjacent the top of upright members 10a, a pair of angle members 12 are respectively mounted in vertically spaced

45 relationship to define therebetween a track 12a. Adjacent the lower portions of uprights 10a a pair of angle members 14 and 16 are mounted in superposed relationship to define therebetween a guide groove 15. A channel member 17 is

mounted intermediate track 12a and groove 15 and serves as a reinforcement and spacer.

An endless conveyor 20 is then mounted on the frame 10 to move therearound in a generally rectangular path. Such conveyor may conveniently comprise a pair of vertically spaced driving chains 20a to which are secured in spaced relationship a plurality of mounting plates 22. Each of the mounting plates 22 is provided with a pair of rollers 24 adjacent its top end thereof which respectively cooperate with the track 12a to provide guided support for the plate 22. In addition, a depending rib 22a is secured to the bottom edge of the plate 22 which projects into the guiding groove 15 to restrain the plates 22 against lateral movements. The chains 20a are secured to the plates 22 by bracket members 22b formed on the rear side of such plates. Chains 20a are then driven at a constant speed around the rectangular periphery of the frame 10 by any suitable form of driving mechanism (not shown).

On each of the plates 22, a bumper bar clamping device 30 is provided. Such clamping device comprises a base 32 (Figures 4 and 5) which is secured to the plate 22 by suitable screws 32a. A stationary jaw 34 is rigidly secured to base 32 by screws 34a. A hole 34f is provided in the stationary jaw 34 adjacent and parallel to the base 32. The hole 34f slidably journals an actuating shaft 36 upon the end of which is adjustably mounted a movable clamp jaw 38. Such end of shaft 36 is threaded as indicated at 36a and movable clamp jaw 38 is provided with a suitable hole to permit the threaded shaft end portion 36a to be freely inserted therein. A pair of nuts 36b respectively disposed on opposite sides of movable clamp jaw 38 permit such jaw to be adjustably positioned on the end of shaft 36.

The other end of shaft 36 is bifurcated as indicated at 36c and pivotally connected by a transverse pin 36d to a link 37. Link 37 is in turn pivoted to the short arm 40a of a bell crank lever 40. The long arm 40b of such lever is provided at its extremity with a manual operating handle 40c. Bell crank lever 40 is medially pivoted on a pin 40d which is suitably mounted in base plate 32. The pin 40d is disposed in alignment with the axis of shaft 36 and hence the bell crank lever 40 and link 37 constitute an over center clamping toggle linkage for controlling the positioning of movable clamp jaw 38. A stop pin 40e may be provided to limit the movement of lever 40.

The fixed clamp jaw 34 is provided with a pair of abutment members 34b which project generally toward the movable clamp jaw 38. Each of such abutment members is in turn provided with a notch 34c adjacent its outer end. The location of notches 34c is so arranged with respect to the configuration of the particular bumper bars which are to be operated on by the machine so that when the medial portion 1a of a bumper bar 1 is positioned as indicated by the solid lines in Figure 5 with one edge thereof resting in the notch 34d defined by the junction of one of the abutment members 34b with the surface 34e of the fixed clamp 34 and the other edge resting in the notch 34c of the other abutment member, then one arcuate end portion 1b of the bumper bar 1, in this case the top end, will be disposed on the conveyor 20 in substantial alignment with the direction of movement of such conveyor. When the bumper bar 1 is reversed end for end with respect to the conveyor

and reclamped by the clamping device 30 in such reversed position, then when positioned in the notches 34c and 34d, as indicated by the dotted lines in Figure 5, the other arcuate end portion 1c of the bumper bar will now be uppermost and will occupy substantially the same spatial position with respect to the conveyor 20 as did the arcuate end portion 1b previously. Hence, the two pairs of notches or abutment surfaces 10 provided on the fixed clamp jaw 34 completely compensate for the effect of non-concentric cross section of any bumper bar which is to be polished on the machine.

The operation of the toggle latch mechanism will be clearly apparent to those skilled in the art. When the bell crank lever 40 is in the position indicated by the solid lines in Figure 4 and abutting stop pin 40e, the movable jaw 38 of the clamping device will be moved to its proximate position with respect to the fixed jaw 34. When bell crank lever 40 is manually shifted to the position indicated by the dotted lines in Figure 4, the movable clamp jaw 38 will be moved to its remote position with respect to fixed clamp jaw 34 and hence a bumper bar 1 may be readily removed or inserted between such clamping jaws.

The clamping devices 30 are mounted on the conveyor support plates 22 in suitable angular relationship with respect thereto so that when a bumper bar 1 is engaged by the clamping device 30 on its central portion 1a, the top arcuate end portion 1b of such bumper bar will be disposed in substantial alignment with the direction of movement of the conveyor 20. By substantial alignment, is meant that the convex exterior surface of such arcuate end portion 1b lies on the average as closely as possible in a horizontal plane, it being appreciated of course that such surface being arcuate it cannot accurately be said to ever lie in a horizontal plane. However, it is believed that those skilled in the art will fully understand the foregoing definition of the manner in which the arcuate end portions are disposed with respect to the direction of movement of the conveyor.

In such position, the concave surface of the arcuate end portion 1b of each bumper bar 1 rests upon an arcuately shaped portion 42a of a supporting rod 42. Support rod 42 is rigidly secured to conveyor plate 22 by being inserted in a bracket 44 provided thereon.

It is therefore apparent that the bumper bars 1, when loaded on the conveyor 20 at the loading position indicated in Figure 1 will pass along the long side of the rectangular path traversed by the conveyor 20 with the topmost arcuate portion 1b disposed substantially parallel to the direction of movement. A plurality of polishing units 50 are provided in spaced relationship along this portion of the path of conveyor 20. Such polishing units comprise a base 50a (Figure 3) which is suitably supported upon the horizontal frame members 10b, a vertically adjustable pedestal 50b, and a support head 50c swivelly adjustable mounted on the top of pedestal 50b. Support head 50c defines bearings 50d for supporting a polishing wheel shaft 50e. A polishing wheel 52 is conveniently secured to one end of shaft 50e while the other end carries a pulley 54 which is belt driven by a suitable electric motor 56 which is also supported on adjustable head 50c. It should be understood that the adjustable mounting of the polishing wheels may comprise any one of several well known forms and no claim is made to the details of such construction.

Each of the polishing wheels 52 may thus be adjustably positioned with respect to the path of movement of the successive arcuate end portions 1b of the bumper bars 1 so as to engage a predetermined area of such arcuate end portions. While it is obvious that any desired number of polishing units 50 may be provided, we have determined that completely satisfactory polishing may be accomplished by the provision of three polishing units 50 on each of the long sides of the rectangular path of conveyor 20.

Therefore, when each successive bumper bar 1 finishes the traverse of the initial long side of the rectangular path of the conveyor, the uppermost arcuate end portion 1b will have been satisfactorily polished. Hence, as the bumper bar 1 traverses the short side of the rectangular conveyor path, a reversing station is provided. At this station, an operator releases each successive clamping device 30 and reverses the position of the bumper bars 1 end for end with respect to the conveyor 20. Each bumper bar 1 is then resecured on the conveyor by closing the clamping device 30. It will be noted that in this reversed position, the transverse edges of the bumper bar 1 engage a different pair of abutment surfaces on the fixed clamp jaw as illustrated in Figure 5 and heretofore described in detail. Therefore, even though the cross sectional configuration of the particular bumper bar is non-concentric, the other arcuate end portion 1c, which is now uppermost, will occupy an identical spatial position with respect to the conveyor 20 as did the other arcuate end portion 1b previously. Therefore, as the bumper bars 1 are carried down the second long side of the rectangular conveying path back toward the loading position, the polishing wheels 52 disposed along such path will effect an identical polishing operation upon the arcuate end portions 1c as was heretofore accomplished on the other arcuate end portions 1b. As each successive bumper bar 1 completes the rectangular conveyor path, it is removed from the conveyor plate at the unloading station and at this point, both arcuate ends of the bumper bar will have been satisfactorily polished.

From the foregoing description, it is apparent that a machine embodying this invention permits the economical polishing of surfaces of members

of irregularly shaped contours. As applied to the polishing of the arcuate end portions of bumper bars, the machine will rapidly produce a completely satisfactory polish on such end portions and requires attention of the operator only in the loading, unloading and reversing operations. Furthermore, the machine will impart a substantially identical polish to both ends of such bumper bars irrespective of the fact that the bumper bar may have a non-concentric cross sectional configuration.

It will, of course, be understood that various details of construction may be modified through a wide range without departing from the principles of this invention and it is, therefore, not the purpose to limit the patent granted hereon otherwise than necessitated by the scope of the appended claim.

We claim as our invention:

20 In a machine for polishing an end of a bumper having a generally U-shaped cross-sectional configuration with one leg of the U shorter than the other, the combination of a conveyor and a clamp secured to said conveyor and arranged to clamp 25 a bumper with an outer end extending beyond said conveyor, said clamp having a first clamping member with a base and spaced arms extending away from the base and having opposed shoulders spaced from said base and a second clamping member movable against the outer surface of the bumper, each shoulder being arranged to receive the edge at the end of the short leg of the U-shaped bumper when the edge at the long end abuts the base of said first clamping member, 35 said shoulders thereby defining two alternate clamping positions in each of which the outer end of the bumper occupies an identical spatial position relative to said conveyor.

THOMAS E. ROBINSON.
